WINDOW

William C. Jones, Tappan, N. Y., and Gustav Siese, Park Ridge, N. J.

Application March 30, 1937, Serial No. 133,784

10 Claims.

(Cl. 20—50)

This invention relates to improvements in windows and more particularly windows of the double-hung sash type.

Such windows are universally popular despite the fact that they have a number of inherent disadvantages. When the sashes are moved into positions with one directly behind the other, the relation which opens the window as wide as possible, one half of the open area of the window frame is blocked by the sashes. This seriously affects the ventilation in warm weather, often making it difficult to cool off bed rooms on Summer evenings even after the air out of doors has become comfortably cool.

15 Washing the outside of double-hung sash windows is difficult when attempted from inside the building. First floor windows can sometimes be reached from the ground, but in the absence of a porch roof, balcony, or other standing room, windows above the first floor can be washed efficiently only by climbing through the window frame and sitting or standing on the sill outside the window. For most housewives this is too strenuous and dangerous, and the result is that 20 upstairs windows are either left dirty or the washing done by a workman who must be paid for the job.

These difficulties are overcome by casement windows, but casement windows have disadvantages of their own. They are much more likely to leak and are difficult to weather strip effectively. If a casement window swings inwardly it takes up space in the room, and furniture must be located so as to leave the window an unobstructed arc in which to swing. If the window is hinged so as to open toward the outside it presents a screening problem. Outside screens cannot be used, and an inside screen must not block access to the window. An inside screen that 25 swings may be just as objectionable as an inwardly swinging casement window.

A sliding sash window with the weight of the sash counterbalanced will remain in any position to which it is moved, but a casement window must be hooked or clamped to insure that it will not blow open or shut.

It has long been recognized that the ideal window would be one having sashes capable of both 30 sliding and swinging movement. The desideratum has been a window having all of the advantages of both sliding sash and casement windows. Many attempts have been made in the past to construct such a window, but so far as we are 35 aware all of these attempts have been imprac-

tical because they require special and expensive frame construction.

It is an object of this invention to provide an improved window construction which obtains both sliding and swinging movement of the 5 sashes. A more specific object of the invention is to provide such a construction which can be conveniently and economically applied to existing double-hung sash windows of the type most commonly used in wooden buildings. The invention 10 can be applied to existing windows, and its simplicity makes new windows in which it is embodied reasonable in cost in comparison with ordinary sliding sash windows.

Windows made in accordance with this invention are easily operated, can be moved up and down when swung open as well as when confined by the stile runways, and are counter-balanced effectively in all positions.

Other objects, features, and advantages of the 20 invention appear or will be pointed out as the specification proceeds.

In the accompanying drawings, forming part hereof:

Fig. 1 is a perspective view of a window embodying the invention, with the sashes swung open.

Fig. 2 is a perspective view, partly broken away, of the window shown in Fig. 1, but with the sashes in the positions occupied when the 30 window is closed.

Fig. 3 is an enlarged sectional view taken on the line 3—3 of Fig. 2, but with the lower sash raised.

Fig. 4 is an enlarged, perspective view of a portion of the pulley stile, the structure being shown removed from the window and placed in a horizontal position.

Fig. 5 is an enlarged, perspective sectional view taken on the line 5—5 of Figure 3.

Figs. 6—8 are enlarged, detail views of parts of the window shown in Figs. 1 and 2.

Figure 9 is a sectional view similar to Figure 3 but taken on the line 9—9 of Figure 2, and with the upper sash lowered.

The window includes a frame 10 of conventional design. An upper sash 11, has a joint near its left edge comprising hinges 13 connecting the main body of the sash with an outer shoe 15 which has the same height and thickness as 50 the main body of the sash so that when the sash is closed, (i. e. in position to slide up and down in the frame) the outer shoe is, in effect, a continuation of the main body of the sash as shown in Fig. 5. A weather strip 17 attached to the 55

outer shoe insures against any leakage of air between the shoe 15 and the other part of the sash, but the window can be made without the weather strip 17 if absolute tightness against infiltration is not essential.

The outer shoe 15 is recessed to fit over a track 19 which is fastened to the pulley stile 20 of the frame by countersunk screws 21 (Fig. 3). The track 19 extends for substantially the full height 10 of the pulley stile.

The recess in the outer shoe 15 has a depth slightly less than the height of the track so that the shoe bears against the track and there is a small clearance between the shoe and the pulley 15 stile.

An inner shoe 23 fits loosely within the track 19 and has a ridge 24 which extends through a slot 26 in the track and contacts with the outer shoe 15. The inner and outer shoes are fastened together by screws 25 which connect the hinge 13 to the outer shoe and thread into the inner shoe. The width of the ridge 24 is slightly less than the width of the slot 26. The height of the ridge 24 is a little greater than the height of the side 25 walls of the slot so that there is clearance for the edge portions of the track below the inner and outer shoes. The ridge 24 is preferably integral with the inner shoe 23 but this is not essential and shims can be used in place of an 30 integral ridge.

The outer shoe 15 slides in the channel or stile runway between the blind stop 29 and parting strip 30 in the same manner as the upper sash of any conventional double hung sash window. The sash 11 is counterbalanced by a weight 32 connected to the sash by a cable 33 which passes over a pulley 34 and connects with a hook 36 at the top of the inner shoe 23 as shown in Fig. 6. Spring balances which are used in place of weights 40 in some modern houses, may, of course, be used in the same way with this invention. The counter-balancing of this invention is just as effective when the sashes are swung open as casements, as when they slide up and down as 45 ordinary sashes.

A second inner shoe 38, shown in Figs. 5 and 7, is connected to the outer shoe 15 at the level of the lower hinge 13. The construction and attachment of the inner shoe 38 is the same as 50 that already described for the inner shoe 23, except that there is no hook 36 because no counter-weight cord is attached to the lower inner shoe 38.

The window has a lower sash 41 which includes 55 an outer shoe 42 (Fig. 2) connected to the main body portion of the sash by hinges 43 near the right edge of the sash. The lower sash has an inner shoe, track, counterweight and other construction similar to the upper sash already 60 described, but the track for the lower sash is located in the stile runway in front of the parting strip 30, that being the runway in which the lower sashes of conventional windows slide.

The upright edges of the sashes 11 and 41 which 65 are remote from their hinged connections with the shoes 15 and 42 slide in the stile runways behind and in front of the parting strip 30 in the usual way. Weather stripping 47 is used in these runways in the illustrated embodiment of the 70 invention. The sashes slide up and down in the frame, the hinges 13 of the upper sash being short enough to pass the lower sash. The window can be locked closed by the usual window lock 49.

The conventional window frame for double 75 hung sash has a removable portion of the pulley

stile through which access may be had to the weight pocket of the frame. In applying this invention to a conventional window, the removable portion of the pulley stile is taken out and the opening enlarged to make it somewhat longer than the height of the sash. While the pieces cut out 5 of the stile can be connected with the removable portion to make the larger movable portion for this invention, it is more economical to save the labor by substituting a single piece of wood previously cut to fit the enlarged cut-out portion. 10

Fig. 5 shows a movable portion 51 of the pulley stile 20. This movable portion has stop plates 52 fastened to the upper and lower ends by screws 53. These stop plates 52 extend behind the fixed portions of the pulley stile 20 above 15 and below the movable portion 51 and prevent the movable portion from moving out beyond the position shown in Fig. 5 in which the surfaces of the movable portion 51 are flush with the surfaces of the fixed part of the stile. 20

The track 19 is made in three sections as shown in Fig. 8, the lengths of the sections being such that the breaks 55 correspond with the upper and lower ends of the movable portion 51 of the 25 pulley stile.

Springs 57 (Fig. 5) fastened to the fixed part of the pulley stile 20 by bolts 58 bear against the top plates 52 and hold the movable portion 51 of the pulley stile in its normal forward position 30 shown in Fig. 5.

When the outer shoe 15 is on that section of the track 19 which is fastened to the movable portion 51 of the pulley stile the sash 11 can be pushed to the left, against the tension of the 35 springs 57, far enough to make its edge which is remote from the hinges 13 come out of the stile runway in which it slides. The sash is then free to swing on its hinges 13.

It is necessary for the parting strip 30 to move 40 back with the movable portion of the pulley stile, otherwise the hinge 13 (see Figure 3) would strike the parting strip and prevent the sash from moving back far enough to clear the guide channel on the other side of the window. The movable 45 portion of the pulley stile on the left hand side of the frame permits the sash 11 to move far enough to the left so that its free swinging edge 50 clears the hinge edge of sash 41, when that sash is swung open, as shown in Figure 1.

The strength of the springs 57 is such that the sash can be easily pushed laterally to clear the stile runway on the side away from the hinges when it is to be swung open in casement fashion, but the springs 57 are strong enough to hold the movable portion 51 of the pulley stile in the position shown in Fig. 5 during the ordinary up and down sliding movement of the sash. Best results are obtained by having the lower spring 57 under 60 somewhat greater tension than the upper spring 65 because the sash is counterbalanced on the hinged side only and that creates a tendency for the entire movable assembly, when in the position shown in Fig. 5, to rotate clockwise about the upper end of the top stop plate 52 as a center, 65 and such movement is prevented by the lower spring 57. Heavier sashes require stronger springs.

The lower sash 41 has a movable portion 60 of the pulley stile behind the track on which 70 the lower sash slides. This movable portion 60 is similar in construction to the portion 51 already described but is, of course, a portion of the forward runway instead of the rearward runway. It is a feature of the construction that the 75

movable portions 51 and 63 of the pulley stiles for both sashes are at the same height above the window sill 62. It is much more convenient to push the sashes laterally to clear the stile runways and swing the sashes open when the sashes are in the lower part of the frame. In fact a short person standing on the floor might not be able to push a sash laterally if the movement had to be made with the sash near the top of the frame and almost out of reach.

It is another feature of the invention that the movable portions 51 of the pulley stiles are longer than the heights of the sashes. This makes it unnecessary to locate the sash accurately before pushing it laterally preparatory to swinging it open.

The invention is not limited to wooden frames or to the embodiment illustrated in the drawings. Various changes and modifications can be made without departing from the invention as defined in the claims.

We claim:

1. A double-hung sash window including a frame having a pulley stile on each side, a pulley near the upper end of each pulley stile, a weight box behind each pulley stile, and channels on the inner sides of the pulley stiles, for guiding both sides of each sash, at least a portion of each stile below the pulley being movable outwardly to permit the sash to move out of its channel on the other pulley stile, and spring means connected to a wall of the weight box and thrusting against the movable portion of the pulley stile in a direction to urge said movable portion inward.

2. A double-hung sash window construction having a vertical hinged joint in at least one of the sashes near one edge so that the sash can swing open about a vertical axis, a pulley stile forming the bottom of parallel channels in which the sashes slide, a section of said pulley stile along the channel for the jointed sash being movable to increase the depth of the channel, spring means connected to a fixed portion of the pulley stile and thrusting against the movable portion of the pulley stile in the direction of the sash, and abutments which stop further movement of said movable portion when it reaches a position flush with the fixed portion of the stile.

3. In a double-hung sash window construction having at least one sash jointed near one vertical edge for swinging movement in addition to its sliding movement, a sash weight connected to the jointed side of the sash and serving as a counter balance for that sash, and having guides in which the jointed sash slides, the guide on the jointed side of said sash being movable in a direction to shift the sash clear of the guide on the opposite side; the improvement of relatively flat guide means and springs yieldably holding the movable guide in a normal position for guiding the sliding movement of the sash, said springs being constructed and arranged to leave a clear space behind the guide means for passage of the sash weight when the guide means is in normal position.

4. In a window frame for double-hung sash constructed to both swing and slide, a pulley stile having a movable portion extending for a height greater than the height of one sash, spring means attached to the outside of the fixed portion of the pulley stile adjacent the ends of the movable portion and bearing against the outside of the movable portion to urge it inward, and abutments in position to stop further inward move-

ment of the movable portion when it comes into alignment with the fixed portion of the stile.

5. A window frame having vertical guides for a sliding sash, and a pulley stile having a fixed portion and an intermediate movable portion of a height at least as great as the height of a sash, two leaf springs connected to the fixed portion of the pulley stile above and below the intermediate portion and extending over the opposite ends of that portion of the pulley stile to hold it in alignment with the fixed portion.

6. A window including a frame having vertical side members, guides on said side members, upper and lower sashes slideable in the guides, at least one of said sashes having a vertical hinged joint near one edge so that the major portion of the sash has a swinging as well as a sliding movement, a single counterbalance connected with the jointed sash on the hinge side of said sash, a movable portion in the side member along the counter balance side of the sash and along an intermediate portion of the length of the side member, and spring means behind the movable portion of the side member yieldably holding the intermediate movable portion in alignment with the fixed portions at the ends of said side member.

7. A window frame for a sliding and swinging window, said frame comprising vertical side members, guides for sliding sashes including an undercut track having two aligned sections extending vertically and supported from the frame, one of said sections being movable transversely in a direction away from the sash, and spring means yieldably holding the movable section of track in alignment with the other section.

8. A double-hung sash window including a frame having parallel guideways along which the sashes slide, said guideways being formed by a parting strip between the sashes and stops in front of and behind the sashes, an undercut track in one of the guideways for the upper sash, a similar track on the guideway for the other side of the lower sash; shoes slideable on the tracks and connecting each sash to its respective track, each of said tracks being fixed along a part of its length and having another part of its length movable sideways far enough to shift the sash out of the guideway for the opposite edge of the sash, and spring means yieldably holding the movable section of track in alignment with the fixed portion of said track.

9. A window comprising a frame having a vertically extending side member, a track connected to said side member, a sash jointed near one vertical edge for swinging movement, means connecting that edge with the track for sliding movement along said track, the connecting means being constructed and arranged to embrace the track and hold the sash against displacement away from the track, the side member having a movable portion and the track including a plurality of sections one of which is at least as long as the sash and connected to the movable portion of the side member, and two springs one at the upper and the other at the lower end of the movable portion of the side member for yieldably holding said movable portion in a position which aligns the track sections, the lower of said springs being under greater tension than the upper to off-set the cantilever loading which the sash imposes on the movable section of track.

10. A double-hung sash window including a frame having a pulley stile on each side and ver-

tically extending members forming two parallel channels along each pulley stile, upper and lower sashes which slide in said channels, a hinged joint in one of the sashes near the right-hand side of that sash, a hinged joint in the other of said sashes near its left-hand side, an undercut track in that channel in which the jointed side of each sash slides, shoes fitting the tracks and holding the sashes to their respective tracks, each of the pulley stiles including a movable portion under the track extending for a distance at least as great as the height of the sash, and each track being in sections, one of which is connected

to the movable portion of the pulley stile, spring means behind the movable portion of each pulley stile urging said movable portion inward toward the pulley stile at the other side of the frame, but yieldable to permit the sash to move sideways until it clears the channel on the side remote from its hinged joint, and abutments which stop further movement of the spring means when the movable track section reaches a position in alignment with the other part of the track. 10

WILLIAM C. JONES.
GUSTAV SIESE.
